WALTER M. GLEASON, OF OAKLAND, CALIFORNIA

COIN-CONTROLLED LOCK

Application filed June 13, 1927. Serial No. 198,356.

My invention relates to a lock utilizing a coin or the like for effecting a primary opening operation thereof.

An object of the invention is to provide a lock of the class described in which knob spindles operable from different sides of the lock are engaged by the coin when the latter is operatively disposed in the lock.

Another object of the invention is to provide a lock of the class described in which a knob spindle directly provides closure means against the insertion of a second coin following a primary operation of the lock.

A further object of the invention is to provide a lock of the class described which is of a particularly simple structure and involves the use of a minimum number of parts.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings,

30 Figure 1 is a front view of the lock.

Figure 2 is an edge view of the lock.

Figure 3 is a plain sectional view of the lock showing the mechanism thereof.

Figure 4 is a view taken on the line 4—4 of Figure 3.

Figure 5 is a view taken on the line 5—5 of Figure 3.

Figures 6 and 7 are fragmentary views showing parts of the mechanism in different operative positions.

Figure 8 is a plan view showing details of the spindle structure and mounting, the parts being positioned as in Figure 3 but axially separated.

In the present embodiment of the invention, the mechanism of the lock is mounted on front and back plate members 6 and 7 respectively which are held in opposed spaced relation by means of suitable spacing members. As here shown, the plate 7 provides the

back wall of the lock casing and also provides the spacing members in the form of portions 8 of the plate 7 bent transversely therefrom at the plate edges and having their extremities 9 bent inwardly in a common plane whereby the front plate 6 may be secured thereto as by screw bolts 11. The plates 6 and 7 are provided adjacent the upper edges thereof with axially aligned openings in which knob spindles 12 and 13 respectively are rotatably mounted with portions thereof extending outwardly from the plates for the reception of knobs 14 and 15. As here shown, the protruding knob receiving spindle portions are rectangular, while the inwardly extending spindle portions are generally cylindrical with their inner extremities in opposed relation.

Extending inwardly from the plates 6 and 7 at each of the spindle perforations thereof, are annular flanges 16 and 17 respectively, the bores of such flanges providing cylindrical bearings for the spindles whereby the spindles may be held in fixed axial relation to the plates for maintaining the mutual alignment of the spindles. Mounted for reciprocation on the inner face 18 of the plate 7 adjacent the spindle 13 is a latch plate 19 carrying a latch bolt 20 at an extremity thereof, such bolt being arranged to be normally held in extended position by means of a compression spring 21 operatively interposed between the other end of the latch plate and a post portion 8. As here shown, the latch plate is formed of a relatively thin strip of metal and is guided for rectilinear movement over plate 7 by reason of the engagement of an upset plate portion 22 and a post 23 in slots 24 and 26 provided in the latch plate. The post 23, it will be noted, is also arranged to overlie the latch plate for holding it against plate 7, and is further utilized in another manner to be hereinafter set forth. The withdrawal of the latch plate and bolt, it will now be noted, is

arranged to be effected by and upon an appropriate rotation of the spindle 13, and as here shown the necessary operative connection between the spindle and latch plate is afforded by means of the engagement of an arm 27 extending radially from the spindle and ar-

ranged to engage a projection 28 provided on the latch plate.

It will now be evident that the withdrawal of the bolt will be effected each time spindle

- 5 13 is appropriately rotated and that, since the spindles are not connected, a rotative movement of spindle 12 may normally be effected independently of any manipulation of the spindle 13, it being noted that the spindles
- 10 12 and 13 are arranged to be respectively operated from the outside and inside of a door on which the lock is mounted. In order that a rotation of the spindle 12 may effect an operative rotation of spindle 13 and thereby
- 15 effect a retraction of the bolt, the spindles 12 and 13 are arranged to simultaneously receive and hold a coin 29 of appropriate denomination whereby the coin will provide such mechanical connection between the spindles as
- 20 will permit the opening operation of the lock from the outer side thereof. Accordingly, and as here shown, the spindles 12 and 13 are respectively provided with diametral slots 31 and 32 extending inwardly from their
- 25 mutually opposed ends and arranged when in aligned relation to together define a coin receiving passage very little wider axially of the spindles than the diameter of the coin 29. Preferably the slot 31 of spindle 12 is of no
- 30 greater depth than slot 32 of spindle 13, and may be of somewhat less depth, as is here shown.

Normally both of the slots 31 and 32 are arranged to be vertically disposed for the co-operative reception of the coin and means are accordingly provided for so disposing the slots. To hold the spindle 12 in its normal position, a spring 33 is utilized, such spring being here shown operatively connected between a radial extension 34 of the spindle and a hook 35 upset from the plate 6 whereby the rotation of spindle 12 in a predetermined direction is urged, it being noted that a contrary rotation of the spindles is required for withdrawing the bolt. As here shown, the rotation of the spindles to withdraw the bolt is clockwise with respect to the spindle axis when the latter is viewed from the outside of the door, and the terms "clockwise" and "counter-clockwise" as hereinafter used, are to be understood as applied accordingly. The extension 34 is arranged, when the slot is normally disposed, to engage a stop 36 provided on the plate 6 adjacent the flange 16. Means are also provided for urging a counter-clockwise rotation of the spindle 13, such means comprising a tension spring 37 operatively connected between the arm 27 and a spacer portion 8. Normally, if left free to turn, the spindle 13 is arranged to be disposed with the slot 32 out of a vertical position in a counter-clockwise direction as shown in Figure 7 and with the arm 27 disposed against a stop 38 provided on the plate 7, it being noted that in such a case the arm 27 lies in spaced

relation from the latch-plate projection 28 and that such arm is arranged to just engage the projection 28 when the spindle is rotated to dispose the slot vertically.

Means are provided for releasably retaining the spindle 13 in position to dispose the slot 32 in its vertical and coin-receiving position, and as here shown such means comprises a pawl 39 pivotally mounted on the post 23 for movement in a plane perpendicular to the spindle axis and arranged for engagement with the peripheral surface of the spindle 13 and a tooth 41 provided thereon and in the plane of movement of the pawl. In this manner, following a rotation of the spindle 13 to withdraw the bolt, and with the pawl engaged against the spindle surface, the return movement of the spindle to the position which it is urged to assume by the spring 37 will be checked to dispose the slot 32 in its vertical position, as shown in Figure 4. The pawl 39, it will now be particularly noted, is arranged to be disposed either for engagement with the tooth 41 or outwardly of the spindle to permit the passage of the tooth thereby so that the spindle may assume its previously mentioned position with the slot 31 out of the vertical. Preferably, and as here shown, the pawl is arranged to be resiliently retained in either one of said positions thereof by means of a tension spring 42 connecting the pawl to a post 43 here shown provided as an upset portion of the plate 7, it being noted that the pivotal point of the pawl is arranged to lie at different sides of the line of action of the spring for said different positions of the pawl whereby the pawl will be positively urged to assume and maintain either one of said positions from an intermediate "dead-center" position.

The slot 31, it will now be noted, is not defined between parallel plane faces as is the slot 32, but is formed rather as of a pair of intersecting and diametrically opposed sector shaped cuts defined between opposed sets of intersecting and angularly related plane faces 44 and 46. Preferably, and as here shown, the faces 44 are mutually parallel and define between their planes a space wide enough to receive a coin, while the faces 46 are similarly related with their planes angularly advanced through a small angle in a counter-clockwise direction from the planes of the faces 44, it being noted that the slot portion defined as between faces 44 is arranged to be disposed vertically when the extension 34 engages the stop 36. The slot 31, it will furthermore be noted, extends axially into the spindle 12 beyond the outer edge of the flange 16 of plate 6, which flange is notched as at 47 to permit the insertion of a coin in the slot when the spindle 12 is disposed in its normal position with faces 44 vertical. In this manner, with a coin in the slot and disposed against the faces 44, the

lower flange portion will form a rest for the coin and so prevent the complete passage thereof through the spindle. A notch 48 is provided in the lower flange portion in counter-clockwise relation to a diameter through notch 47 whereby a coin positioned substantially against the slot faces 46 when the spindle 12 is normally disposed will be enabled to escape from the slot, it being noted that no coin retaining means are provided on or in connection with the spindle 13 and that the rotative relation of spindle 13 to spindle 12 determines the disposal of the coin in the slot of the latter as is hereinafter set forth in detail.

Extending from the pawl 39 toward the spindle 13 is an arm 49, which arm, when the pawl is operatively engaged against the spindle, is arranged to be so engaged by a coin in the spindle that when the latter is turned to withdraw the latchplate, the pawl will be set in its inoperative position as clearly shown in Figure 6. As here illustrated, the spindle 13 is transversely recessed at a side thereof to receive the arm 49 for engagement with the coin, the relation of the arm and recess being such that the displacement of pawl 39 will only occur when there is a coin in the spindle, so that a turning of the spindle to withdraw the latch when no coin is in the spindle, does not effect the disposal of the pawl in inoperative position. The inner surface 51 of the recess is so related to the arm 49 that on a return movement of the spindle following the release thereof, the surface 51 will engage the arm to restore the pawl to its operative relation to the spindle, it being noted, however, that such restoration of the pawl to its operative position is arranged to be effected only after the tooth 41 has passed its position for engagement with the pawl, whereby the spindle 13 is permitted to assume the position shown in Figure 7. In this manner, it will now be clear that when a coin is operatively disposed in the slot of spindle 13, the movement of the latter from its coin receiving position to withdraw the latch bolt renders the pawl inoperative whereby release of the spindles permits spindle 12 to resume its normal position and permits the spindle 13 to move back beyond its coin receiving position to dispose the coin slot thereof obliquely with the coin against the faces 46 of the slot of spindle 12. In this manner the coin will be moved to register with the notch 48 of the flange 16 and is thus allowed to escape from its engagement in the spindles. When the spindle 13 is thereafter rotated from the inside of the door to withdraw the latch bolt, the pawl will ride over the tooth whereby the spindle may be caught and held in coin receiving position upon being released following such movement. The range of movement of the pawl is limited by means of a stop pin 50 extending from the plate 7

between the pawl and spindle and arranged for engagement with the pawl or its arm 49.

A casing 52 is provided for enclosing the mechanism now described, such casing having a top wall portion 53 closely overlying the spindles 12 and 13 and provided with a coin receiving perforation 54 disposed to overlie the slots 31 and 32 when they are in cooperating coin receiving position whereby a coin may be introduced into the mechanism. When, however, the spindle 13 is disposed as in Figure 7, a portion 56 of its surface will be disposed across the perforation 54 whereby the passing of a coin through the latter and into the lock will be positively prevented. Preferably, and as here shown, the perforation closing portion 56 of the spindle 13 is extended axially to overlie the slot 31 of the spindle 12 and the notch 47 of flange 16, such flange and spindle being here shown as of slightly smaller diameter than the spindle 13 to permit such relation. In this manner, a complete closure of the perforation 54 is arranged to be effected whenever the insertion of a coin is to be prevented. To still more positively indicate the closure of the perforation 54, a suitable symbol 57, such as the word "Occupied", may be provided on the spindle portion 56, as is herewith particularly disclosed.

The casing 52, it will be noted, is arranged to cooperate with the plate 7 to define a coin box adjacent the bottom thereof, and is provided in its front face 58 with a suitably locked door 59 for permitting access to the coin box by an attendant.

With the foregoing description of the lock in mind, a cycle of operations of the lock will now be set forth. Having the spindles set in their cooperating coin receiving position with their coin receiving slots in registration with the casing perforation, a coin dropped through the perforation would fall downwardly through the passage provided by the spindle slots 31 and 32 until it comes to rest on the flange 16. A clockwise rotation of spindle 12 by means of the outer knob 14 will first cause the surfaces 46 of the slot of spindle 12 to engage the coin, after which further rotation of the spindle 12 will rotate the coin about the spindle axis to effect a rotation of spindle 13 and a withdrawal of the latch plate 19, while the coin, by reason of its engagement with the pawl arm 29 will at the same time cause a disposal of the pawl 39 in inoperative relation to the tooth 41. Release of the knob 14 will now permit the spindle 12 to resume its normal position while the spindle 13 will, through failure of the pawl 39 to engage tooth 41, assume a position to dispose the portion 56 thereof under the casing perforation 54 for closing the same, and at the same time dispose the coin for registration with the lower notch 48 of flange 16 whereby the coin may escape from its operative posi-

tion in the spindles, restoration of the pawl 39 to its operative position but behind the tooth 41 being also effected. Upon an exit operation of the spindle 13, that is, by rotating same with the inner knob 15, the tooth 41 will be moved from under the pawl to the opposite side thereof, whereby upon a return movement of the spindle 13 following the release thereof, the latter will be stopped and held in its coin receiving position and the lock is thus restored to its original condition for the reception of another coin and operation from the outside.

It will now be noted that the lock mechanism of my invention comprises a minimum number of moving parts, and is particularly positive in its functioning. Furthermore, since the only mechanical connection required between the spindles 11 and 12 is provided by the coin itself, each of the spindles and its associated mechanism can be independently mounted on a different plate member whereby assembling of the lock structure may be very much simplified. Also, the use of a spindle 23 as a closure means for the coin receiving perforation of the casing is an important factor in minimizing the required number of parts.

I claim:

1. In a coin controlled lock, a normally extended bolt, members rotatable about a common axis and arranged to be rotated from opposite sides of said lock, one of said members being operatively connected to said bolt for effecting the withdrawal thereof and the other of said members being normally rotatable independently of said first member, means utilizing a coin to directly connect said members whereby an appropriate manipulation of said second member will actuate said first member to withdraw said bolt, means operative to retain the coin in operative relation to said members prior to and during the withdrawal of said bolt by means of said second member, means cooperating with said last means and members to automatically release said coin from its operative position following said withdrawal of said bolt and to prevent the operative association of a second coin with said members, and means cooperating with said members operative upon a subsequent withdrawal of said bolt by said first member to thereafter permit the operative association of said second coin with said members.

2. In a coin-controlled lock, a casing providing a coin slot, a normally extended bolt, opposed members rotatable about a common axis and arranged to be actuated from opposite sides of said lock, one of said members being operatively connected to said bolt for effecting the withdrawal thereof and said members cooperatively providing a coin receiving passage for the reception of a coin from said slot to operatively connect the other member to said first member whereby an

appropriate rotation of said second member will effect the withdrawal of said bolt, and means for rotating one of said members to close said slot following the insertion of a coin in said passage and the withdrawal of the bolt by means of the rotation of said second member.

3. In a coin-controlled lock, a casing providing a coin slot, a normally extended bolt, independent and axially aligned knob spindles operative from opposite sides of the lock and provided at their inner portions with means cooperative to define a coin receiving passage lying in a plane parallel to the spindle axis and normally including said coin slot, whereby a coin disposed in said passage will connect the spindles for the joint operation thereof, means operatively connecting one of the spindles with said bolt and means operative when a coin is disposed in said passage to position said last spindle to close said slot following the withdrawal of said bolt by means of the rotation of the spindles.

4. In a coin-controlled lock, a normally extended latch bolt, a lock mechanism including knob spindles operable from opposite sides of the lock, means operatively connecting one of said spindles with said latch bolt, means utilizing a coin to operatively connect the other of said spindles to said first spindle, a casing for said lock providing a coin slot normally open to permit the operative insertion of a coin in said mechanism, means utilizing a spindle to close said slot following a withdrawal of said bolt by means of the actuation of said second spindle, and means thereafter operative to reopen said slot following the withdrawal of said bolt by means of the actuation of said first spindle.

5. In a coin-controlled lock, a casing providing a coin slot, a normally extended bolt, a rotatable knob spindle comprising independent spindle sections formed to cooperatively provide a coin slot, which sections when a coin is deposited in the slot thereof are jointly operable to effect a retractive movement of said bolt, one spindle section being arranged in one position thereof to serve as a closure for said coin slot in the casing, and releasable means automatically operable to retain said spindle in slot closing position following a retraction of the bolt thereby.

6. In a coin-controlled lock, a casing providing a coin slot, a normally extended bolt, independently rotatable knob spindle sections for operating the bolt formed to cooperatively provide a coin receiving slot, said spindle sections being arranged in one position to receive in the slot thereof a coin which has been inserted through said casing slot and arranged in another position to serve as a closure for said slot in the casing, and means operative to alternately hold said spindle in said positions.

7. In a coin controlled lock, a normally ex-

tended bolt, members rotatable about a common axis and arranged to be rotated from opposite sides of said lock, one of said members being operatively connected to said bolt for effecting the withdrawal thereof and the
5 other of said members being normally rotatable independently of said first member means utilizing a coin to directly connect said members whereby an appropriate manipulation of said second member will actuate said first member to withdraw said bolt, means including a portion of one of said rotatable members automatically operative following a bolt withdrawing manipulation
10 of said second member to prevent the operative association of a second coin with said members, and means operative by and upon a subsequent withdrawal of said bolt by said first member to thereafter permit the operative association of said second coin with said
15 members.

8. In a coin controlled lock, independent and axially aligned spindles operative from opposite sides of the lock and formed to cooperatively provide a coin receiving slot whereby a coin deposited in said slot will connect said spindles for joint operation, a lock casing having a coin slot arranged to register with the spindle slots and one of said
25 spindles having the greater portion of the spindle provided coin slot, and an extension on said last named spindle and providing with the spindle a portion for closing the casing slot in one position of the spindle.

30 9. In a coin controlled lock, independent and axially aligned spindles operative from opposite sides of the lock and formed to cooperatively provide a coin receiving slot whereby a coin deposited in said slot will connect said spindles for joint operation, a lock casing having a coin slot arranged to register with the spindle slots and one of said spindles having the greater portion of the spindle provided coin slot, and an extension on said last named spindle and providing with the spindle a portion for closing the casing slot in one position of the spindle,
35 and indicia denoting a condition of the lock arranged on the spindle carrying the extension and appearing on said extension.

40 50 In testimony whereof, I have hereunto set my hand at Oakland, California, this 8th day of June, 1927.

WALTER M. GLEASON.
